UNITED STATES PATENT OFFICE.

EDWIN R. LOCKE, OF KEENE, ASSIGNOR, BY MESNE ASSIGNMENTS, TO HIMSELF, AND ALDEN W. STEVENS, OF EAST SULLIVAN, NEW HAMPSHIRE.

APPARATUS FOR TANNING HIDES.

SPECIFICATION forming part of Letters Patent No. 278,981, dated June 5, 1883.

Application filed February 26, 1883. (No model.)

To all whom it may concern:

Be it known that I, EDWIN RUTHVIN LOCKE, of Keene, in the county of Cheshire, of the State of New Hampshire, have invented a new and useful Improvement in Apparatus or Means for Tanning Hides; and I do hereby declare the same to be described in the following specification and represented in the accompanying drawings, of which—

10 Figure 1 is a top view, Fig. 2 a side elevation, and Fig. 3 a longitudinal section, of a set of tan-vats provided with my invention, the nature of which is duly set forth in the claim hereinafter presented, such invention 15 being for the purpose of facilitating the handling of hides, or transferring them from one vat to another successively in the series, during the process of tanning them.

It is well known that in effecting the tanning of hides it has been common to employ 20 a series of vats, the tanning-liquor of each being stronger in tanning than that of the next preceding vat. The hides, strung or attached together, were, after having been suffered to 25 remain in each vat a sufficient period of time, removed therefrom and transferred into the next succeeding vat of the series. Prior to my invention such transferring of the hides has 30 usually been accomplished by manual labor, with hooks or other suitable implements, thereby consuming much time and skill, which by my improvement is very materially reduced, as by means of it a small boy can accomplish 35 in a given time what heretofore has required the labor of some two or more men to effect. Attempts have also been made to accomplish 40 the result by mechanism in some respects analogous to that herein described, though differing therefrom in other and important particulars, a mechanism for such purpose being represented in the United States Patent No. 219,537.

In the drawings, A A' A² denote three tan pits or vats, arranged in the order as shown. 45 Extending along them is a rail way or ways, B B', for a carriage, C, to run upon, such carriage being provided, by preference, with wheels a, to rest and run on the rails or ways B B'. This carriage supports a revolute reel,

D, whose journals extend into suitable bearings at or in the tops of the posts b b of the carriage. One of the said journals projects beyond its post, and has fixed concentrically on it (the said journal) a grooved wheel or pulley, c, about which and two other such wheels, d e, an endless band, f, is run. The wheels d e are supported by and so as to revolve freely in two posts, g h, arranged with the vats in manner as represented, there being on the axle of one of such wheels a crank 50 or a driving-pulley for revolving it. The endless band goes from the first wheel, d, to and entirely around the pulley or wheel c, thence to and half-way around the wheel e, from which it will be seen that on revolving the 55 wheel d the reel will be put in revolution, and that it with its sustaining-carriage may be moved from one vat to the other throughout the series, first in one direction and next in the opposite, and in the meantime have the 60 endless band and the wheel c in engagement.

In using the revolute reel the carriage is 65 to be moved so as to bring the reel directly over the partition between the first and second of the vats, after which one of the end hides 70 of the string in the said first vat is to be raised out of the vat and thrown over the reel, which may be supposed to be in revolution in a proper direction, in which case it will cause the hides successively to be drawn from the 75 first vat and transferred or dropped into the second one. This process of removing the string of hides from vat to vat is to be repeated from time to time, in manner and by means of the revolute reel, as circumstances may 80 require.

I claim—

The combination of a series of tan-vats and the revolute reel and its supporting-carriage, the sustaining rails or ways of such carriage, 90 and the endless band and its three supporting-wheels, adapted and arranged substantially and to operate as set forth.

EDWIN RUTHVIN LOCKE.
